CASEMENT SCREEN AND THE LIKE

Karl F. Jorss, Washington, D. C., assignor to
Crittall Manufacturing Co., Inc., Washington,
D. C., a corporation of Delaware

Application October 19, 1932. Serial No. 638,617

7 Claims. (Cl. 189—64)

The invention relates to certain improvements in auxiliary closures, such as screens and storm sashes, for use in connection with casement windows, and has for its object to provide such closure devices with resilient sealing means to close the opening between the frame of the auxiliary closure and the casement frame and also between the casement frame and the casement sash.

The invention is illustrated in the accompanying drawing, in which:—

Fig. 1 is a lateral sectional elevation of a typical casement window to which the invention has been applied.

Fig. 2 is an enlarged fragmentary front elevation.

Fig. 3 is a section on line 3—3 of Fig. 2.

Fig. 4 is a fragmentary section of a storm sash.

Referring to Figs. 1 to 3 of the drawing, 1 indicates a casement frame of conventional form involving the usual Z bars of metal fashioned to fit the opening in the wall of a building structure and 2 indicates the cooperating sash of the casement window, which is similarly formed of Z bar sections and is connected to the frame 1 by the usual hinges, not shown, to permit the sash to be swung to open or closed position, the sash being provided with the usual glass panel 3. It will be understood that the casement window construction is merely exemplary and, instead of the particular form shown, it may involve any of the usual forms now generally employed in building construction.

It is customary practice to provide casement windows with removable screens secured to the inner or outer face of the casement frame, depending upon whether the casement sash swings inwardly or outwardly with respect to the frame. As shown in the drawing, the casement window is of the former type, namely, with an outwardly swinging sash. Therefore, the screen is shown as secured to the inner or room face of the casement frame. It is also highly desirable, and frequently quite difficult, to apply weather striping or sealing means to casement windows for the purpose of sealing the openings between the meeting portions of the casement frame and sash, when the latter is closed, to exclude air, moisture, dust and the like. Likewise, in many cases, it is found necessary or desirable to fit casement windows of this general character with removable storm sash, which serves the usual and intended purposes of such auxiliary closure devices in winter seasons or in cold climates.

As stated, the present invention involves the provision of an auxiliary closure, either in the

form of a removable screen or a removable storm sash, which may be readily applied to and removed from operative relation with respect to the casement window and which comprises, in its component structure, a sealing strip so disposed as to effectively close the cracks or openings between the auxiliary closure and the frame of the casement window and also similar cracks or openings between the casement frame and the sash, when the latter is in closed position.

In its preferred form, when the auxiliary closure is a screen, as illustrated in Figs. 1 to 3, it comprises a frame 10 which conforms generally to the shape of the casement frame 1, so as to partly overlie the abutting face of the casement frame adjacent the inner edge of the latter. The frame 10 is preferably made of metallic channel sections separated by longitudinal ribs, the outer channel 11 being adapted to receive the sealing or packing strip and the inner channel 12 adapted to receive the turned edges of the woven wire screen material 13, which is locked securely in the frame by the usual keys or splines 14 of spring metal or the like. The sealing strip 15 may be of any suitable resilient material, such as rubber, felt or the like, that may be readily forced into and held securely in the groove or channel 11, which extends entirely around the frame 10. The said sealing strip is preferably preformed with a laterally projecting flange 16, 85 which, as shown, overhangs the flange or rib dividing the channels 11 and 12, the flange also being of sufficient thickness to abut and be compressed against the inner face of the sash frame, when the sash is in closed position. As clearly indicated in the drawing, the projecting portion of the resilient packing strip 15 is of such form and dimensions as to cause it to be compressed against the face of the casement frame, against the inner edge of said casement frame and also 95 against the inner face of the sash, in the relation indicated more particularly in Fig. 3, and, therefore, to constitute an effective seal for the openings which normally exist between the screen frame and the casement frame and between the 100 casement frame and the casement sash.

The screen may be secured in proper abutting relation with the face of the casement frame by any appropriate means, which will be effective in clamping the screen firmly against the casement frame with sufficient force to press the projecting portions of the sealing strip 15 into engagement with the aforesaid surfaces of the casement frame and sash. A relatively simple but effective means for securing the screen to the 110

casement frame comprises two or more Z-shaped supporting brackets 20 fastened to the lower rail of the casement frame, the outer leg of each bracket preferably being inclined outwardly and upwardly to afford a wedging fit with the lower rail of the screen frame. The stiles or side members of the screen frame and also the top rail, in the case of relatively large screens, are provided with lip-like extensions, such as 22, which 5 may be spot welded or otherwise secured to the screen frame, at proper intervals, and which are adapted to be engaged by the heads of bolts or threaded turn buttons, such as 23, secured to the face of the casement frame. These simple 10 securing devices are effective in clamping the screen securely in position against the face of the casement frame and admit of the screen being applied to or removed from position expeditiously and without the need of special tools.

20 As hereinbefore stated, the invention is also applicable to storm sashes adapted to be applied as auxiliary closures to casement windows, such storm sashes to be employed alternatively with the screens, that is to say, when the screens are 15 removed at the end of the summer season, they may be immediately replaced by the storm sash for use throughout the late fall, winter and early spring. As illustrated in Fig. 4, the storm sash differs structurally from the screen only in the 20 means for securing the glass 13' in the frame. As shown, the frame comprises metal sections 10' having one channel 11' substantially identical with the channel 11 in the screen frame and in which channel the same form of resilient 25 packing strip is secured. In order, however, to secure the glass pane or panes in the frame, the inner portions of the frame members are provided with stepped flanges 14' and 14'' adapted to receive the cement or other medium by means 30 of which the glass is fixed in the frame. As shown, the shorter flange 14' is adapted to receive the flanged edge of a suitable channel-like finishing strip 17, which surrounds and protects the portions of the cement which would be exposed otherwise.

35 What I claim is:

1. An auxiliary closure for casement windows, comprising a frame adapted to be secured in overlapping relation to a face of the casement frame, and a strip of resilient material carried by, extending around and projecting from the

face of said frame that abuts the casement frame to effect a seal between the frame and the casement frame and between the latter and the sash.

2. An auxiliary device as set forth in claim 1, in which the sealing strip is secured in a groove 80 in the closure frame.

3. An auxiliary closure for casement windows, comprising a frame adapted to be secured in overlapping relation to the casement frame, said frame having a groove extending around the face thereof that abuts the casement frame, and a sealing strip secured in and projecting from said groove to seal the openings between the frame and the casement frame and between the latter and the sash.

4. An auxiliary closure for casement windows, comprising a frame adapted to be secured in overlapping relation to the casement frame, said frame having a groove extending around the face thereof that abuts the casement frame, and a sealing strip secured in and projecting from said groove and having a laterally projecting flange adapted to engage the inner marginal edge of the casement frame and the adjacent face of the sash.

5. An auxiliary closure for casement windows, comprising a frame of a size to partly overlap the casement frame and having a groove extending around the face thereof that abuts the casement frame which groove is partly overlapped 10 by the inner edge of the casement frame, and a packing strip in said groove adapted to engage the face and inner edge of the casement frame and the inner face of the sash.

6. A screen for casement windows, comprising 11 a frame formed of metal channel sections and adapted to partly overlap the casement frame, and a packing strip projecting from a channel in the screen frame so as to engage the adjacent face and inner edge of the casement frame and 11 the inner face of the sash.

7. An auxiliary closure for casement windows, comprising a frame adapted to overlie one face of the casement frame and having a resilient strip carried by and extending around the face that 12 abuts the casement frame and so disposed as to close the opening between said frame and the casement frame and the opening between the casement frame and sash.
